DISPENSING SPOOL FOR SURGICAL THREAD

Donald S. Jurnove and Samuel Hammer,
New York, N. Y.

Application June 1, 1948, Serial No. 30,356

4 Claims. (Cl. 242—138)

1

This invention relates to spools for use in connection with ligatures or thread used for suturing. It is a fact well known to practicing surgeons that spools for surgical thread now available for use, are unsatisfactory for several reasons, the principal reason being that they are so difficult to manipulate under the pressure and tension of a surgical operation. Very frequently, fumbling takes place with a consequent loss of valuable time, and indeed not infrequently does the surgeon drop the spool and the thread, and thus contaminate it. Hence, it is customary to have several ligature spools handy for each operation so that in the event that any one or more of such spools should become unsterile, there would be others available to take their place without interruption of the surgical operation.

The present invention is designed to eliminate these difficulties and inadequacies which are inherent in conventional surgical-thread spools. In the present device, a positive quick-acting release is provided to enable the surgical thread to be removed from the spool with the greatest of ease and speed. In the present invention there is also a quick-acting locking mechanism which instantaneously locks the spool to prevent further issuance of the thread therefrom.

It is accordingly the principal object of this invention to provide a surgical thread spool which has an extremely quick-acting release mechanism and an equally quick-acting locking mechanism for controlling the issuance of the thread or ligature from the spool.

Another principal object of this invention which is corollary thereto is the provision of a ligature spool of the character described whose quick-acting release and locking mechanisms are instantly available to the surgeon for immediate and effortless use.

Still another object of this invention is the provision of a spool in which the surgical thread may be released for use by simply applying a squeezing force upon the device and wherein the thread may be locked against further issuance therefrom by simply releasing the spool from such squeezing action.

A still further object of this invention is the provision of a spool as described, which is comprised of exceedingly few, simple parts which may very readily be made at relatively low cost.

Still another object of this invention is the provision of a spool as described, which may very easily be sterilized in conventional sterilizing apparatus, the thread being itself sufficiently exposed to be sterilized at the same time and by the same means as the spool itself is sterilized.

Other objects of the invention include the provision of a spool as described, which may be rewound with surgical thread after its original supply thereof is exhausted.

2

Preferred embodiments of this invention are shown in the accompanying drawing, in which:

Fig. 1 is a side view of the first embodiment.

Fig. 2 is a plan view thereof.

Fig. 3 is a vertical section therethrough, showing the spool in locked position.

Fig. 4 is a view similar to that of Fig. 3, showing the spool in unlocked position.

Fig. 5 is a sectional view showing a modification 10 of this invention.

Fig. 6 is a sectional view of a further embodiment of this invention.

Fig. 7 is a sectional view of still another embodiment of the invention.

Referring now to the first four figures of the drawing, it will be noted that a spool or reel 10 is mounted in spool holder 11, as is a releasing and closure disc 12. The cross-sectional views of the spool show that it should preferably be made of a single piece of material such as die cast metal. It has a hollow hub 13 which is provided with holes 14. Its spaced, substantially circular flanges 15 are also provided with holes 16. These several holes have a definite function, namely, that of allowing a sterilizing medium to enter into contact with the thread 17 which may be wound thereon. In other words, when the spool and spool-holder as a whole are put into a sterilizing apparatus, the object is not to sterilize the spool alone, but also the thread which the spool carries. Were it not for holes 14 and 16, the sterilizing agent might not be able to reach some of the inner windings of the thread. With these holes an excellent job may be done to sterilize both the spool and its suturing thread.

The spool should also preferably be a one-piece affair. It may be of metal, the same as is the spool itself. The spool holder is provided with a floor or base portion 20 and with a plurality of uprights or arms 21. These arms are not perfectly rigid members but instead are somewhat resilient and springy. They may be spread apart and then when released, they will spring back to their original positions. In Fig. 4, arms are shown in extended or sprung position. It will be noted that when the arms are held in sprung position, they are out of engagement with the upper flange of spool 10. The spool is thus free to rotate. In Fig. 3, the arms are shown in released condition, and it will be noted that they serve as a brake and engage at least one of the two flanges of the spool. The arms are still in a slightly sprung condition to enable them to bear sufficiently hard against the spool flange to prevent the spool from rotating.

The means by which arms 21 may be moved out of clamping engagement with the spool flange is the combination release and closure disc member 12 previously mentioned. This member is substantially disc-shaped, and is held in place above

the spool by means of grooves or notches 22 formed at the top free ends of arms 21. One of the walls forming each of said grooves or notches 22 slopes inwardly and downwardly to form a cam face which engages the rounded peripheral edge of the disc-shaped member 12. When the disc member 12 is pressed downwardly in the direction of the arrow shown in Fig. 4, the engagement of its peripheral edge with the cam faces which grooves 22 form, causes an outward spreading movement of arms 21 into sprung condition. As has already been indicated, when the arms are sprung outwardly, they disengage the upper flange of the spool, the lower flange being free of the arms, thereby freeing the spool for rotary movement when it is desired to remove some of the surgical thread therefrom. When the disc-shaped member 12 is released, the arms 21 spring back to the position which they are shown to occupy in Fig. 3, and their respective cam faces are thereby caused to act upon the disc-shaped member and to push it upwardly into its non-active position which is shown in Fig. 3.

In Fig. 5, a spool 30 substantially similar to spool 10 is shown mounted in a modified spool holder 31, which is generally similar to holder 11. However, in this form, the spring arms are so constructed as to prevent removal of the spool 10 from the holder 31, and thus prevent substitution of the spool by another spool; the idea being that the spool and holder must remain intact, either to be discarded when the spool is emptied of thread, or have new thread replaced on the spool. To that end, it will be noted that the base of the holder 31 is provided with a centrally-located aperture 32 which is aligned with the bore that extends through the hub of spool 30. A crank handle 33 (shown in dot and dash lines in the drawing) may be inserted into the hub of the spool through the aperture in the floor of the spool holder 31. A relatively tight fit should be provided between the entering end of the crank handle and the hub of the spool to enable the crank handle to rotate the spool when the handle is itself worked. Rotation in one direction will, of course, wind the thread upon the spool, after which the crank handle 33 may be removed.

To provide against removal of the spool from the spool holder, stop members 34 may be formed on the inner sides of the arms of the holder. These stop members may be beveled at their upper surfaces to enable spool to spread the arms 21a to pass them when it is being slipped into the spool holder. The under surfaces of the stop members 34 should be non-beveled to prevent the spool from camming or wedging them out of the way for removal of the spool from the spool holder.

Another embodiment of this invention, as shown in Fig. 6, is provided with a spool 40 carried within a spool holder 41. There is no substantial difference between spool 40 and spool 10 first above described. Spool holder 41 looks quite different from holder 11 above described, but they possess major features in common. Holder 41, like holder 11, has a floor and it also has a side wall or walls which confine the spool in much the same manner as do the arms 21 of holder 11. Side wall 42 of holder 41 is shown to be continuous, but it will be understood that it may also be made non-continuous in the sense that arms 21 are not continuous with each other.

Holder 41 is not, however, provided with cam faces similar to those which are formed in

grooves or notches 22 in arms 21. There is no cam action between release and locking member 43, shown in Fig. 6, and the side wall 42 of the spool holder shown in said figure. A cam action is provided, however, between said release member 43 and a locking spring member 45, carried within said spool holder and extending into the hub of the spool. Extending downwardly from release member 43 is an annular flange 46 whose inner wall is beveled downwardly and outwardly. It is this beveled wall which serves as a cam and which engages the spring members 45 to compress them when it is desired to free the spool for rotation.

It will be observed in Fig. 6 that the spring member 45 rests upon the floor of the spool holder to which it may be fixedly connected. It has a centrally-extending, upwardly-projecting portion which enters the hub of the spool. This upwardly-extending portion may comprise a plurality of fingers roughly corresponding to the arms of the first embodiment herein described. These fingers are made of spring metal, but whereas arms 21 tend to spring inwardly when released, these fingers tend to spring outwardly. When these fingers spring outwardly, they engage the inside wall of the spool hub and thereby lock the spool against rotation. It will be noted that the cam-shaped flange 46 engages the outer surfaces of fingers 45 at their upper, free ends. When the disc 43 is pushed downwardly, its cam-faced flange acts upon fingers 45 and presses them inwardly toward each other. They are thereby forced to disengage the hub of the spool which is thereby released for rotary movement. To lock the spool against rotation, the disc 43 is simply released and the spring members 45 wedge said disc member upwardly and out of the way, and engage the hub of the spool to prevent rotation thereof. It will be noted that an inwardly-extending bead or flange 42a is provided at the top end of wall 42 and serves as a stop member for the upwardly moving disc member 43, thus retaining it in the holder.

It will be noted that there is identity of principle of operation between the first two embodiments of the invention herein described. In both cases, spring members engage the spool to prevent it from rotating, and in both cases, a cam is used to engage the spring members and to move them out of clamping contact with the spool.

A further embodiment of this invention is shown in Fig. 7, and is also provided with a spool 50 and a spool holder 51. Again there is no great difference between spool 50 on the one hand and spools 10, 30 and 40 on the other hand. The holder 51, however, is comprised of two cup-shaped members 52 and 53. It will be noted that the cover overlaps the lower member slightly, where they meet, and a snug or friction fit is provided between the two members to hold them together. The holder is made in two parts to simplify the operation of inserting a spool therein or removing it therefrom. However, if desired, the two parts may be soldered or otherwise united, to avoid re-use of the holder. A release member 55 which resembles a push button having an elongated stem 57 connected thereto extends through a hole in the cover 53 into the hub of spool 50. A coil spring 56 is mounted on the stem 57 of said release member 55 and is affixed to said stem at its lower end. At its upper end, the spring is affixed to the cover 53 of the spool holder. It will be understood that this coil spring

becomes smaller in diameter as it increases in length, that is, when the spring is caused to expand its coils, grow smaller in diameter. Hence, when a downward force is applied to the release member 55, thereby causing downward extension of spring 56, the diameter of said spring will become smaller. It will be seen in Fig. 7, that before this downward movement of the release member begins, the spring is sufficiently large in diameter to engage the hub of the spool and thereby prevent the spool from rotating. When the release member is moved downwardly, the diameter of the spring is reduced sufficiently to remove it from contact with the spool hub, thereby freeing the spool for rotation.

It will be appreciated that the embodiments hereinabove described are illustrative in character rather than limitative. Their construction may be modified in many respects without passing beyond the limits of the scope of the invention. In principle, however, it is important that a spring member be provided to engage the spool to prevent rotation thereof, and a release also be provided to disengage the spring from the spool to free the spool for rotation.

Having thus described our invention, what we claim as new and desire to secure by Letters Patent, is:

1. A spool for surgical thread comprising a base, a spool mounted on said base, spring members extending upwardly from said base to encompass the spool and engage a flange thereof to hold the spool in place on said base and also to prevent rotation thereof, and a release member confined between said spring members for disengaging said spring members from the spool to free the spool for rotation.

2. A spool for surgical thread comprising a base, a spool mounted for rotation on said base, a plurality of spring members on said base surrounding said spool and clamping it in place on said base, and a wedging member engageable with said spring members to wedge them out of clamp-

ing action with the spool to free the spool for rotation on said base.

3. A spool for surgical thread comprising a base, a spool mounted for rotary movement on said base, spring members extending perpendicularly from said base surrounding and engaging said spool to prevent rotation thereof, and cam means to cam said spring members out of clamping engagement with the spool to free the spool for rotary movement.

4. A spool for surgical thread comprising a base, a spool mounted on said base for rotary movement thereon, a plurality of relatively springy side members connected to said base, and surrounding said spool, said side members being normally in tensioned engagement with said spool to prevent rotation thereof, cam faces formed on the insides of said side members, and a substantially disc-shaped member supported by said side members and engageable with the cam faces on said side members whereby the side members may be cammed out of clamping engagement with the spool to free the spool for rotary movement.
